CLAIM

The ornamental design for a display screen with animated graphical user interface, as shown and described.

DESCRIPTION

FIG. 1 is a front view of the first image in a first sequence for a display screen with animated graphical user interface; FIG. 2 is a front view of the second image; FIG. 3 is a front view of the third image; FIG. 4 is a front view of the fourth image; FIG. 5 is a front view of the fifth image; FIG. 6 is a front view of the sixth image; FIG. 7 is a front view of the seventh image; and, FIG. 8 is a front view of the eighth image.

The appearance of the animated graphical user interface sequentially transitions between the images shown in FIGS. 1-8. The process or period in which an image transitions to another forms no part of the claimed design.

The broken lines shown in FIGS. 1-8 illustrate portions of the display screen with animated graphical user interface that form no part of the claimed design.
